UNITED STATES PATENT OFFICE.

ALLAN E. LARD, OF WASHINGTON, DISTRICT OF COLUMBIA, ASSIGNOR TO THE METALLIC SHAFT COMPANY, OF WILMINGTON, DELAWARE, A CORPORATION OF DELAWARE.

HANDLE OR GRIP SURFACE.

Application filed January 27, 1921. Serial No. 440,373.

To all whom it may concern:

Be it known that I, ALLAN E. LARD, a citizen of the United States, residing at Washington, in the District of Columbia, have invented certain new and useful Improvements in Handles or Grip Surfaces, of which the following is a specification.

This invention pertains to handles or grip surfaces designed more particularly for use in connection with sporting goods such as golf clubs, tennis racquets, and the like, though the same is applicable for employment in conjunction with tool handles, steering wheels, and similar structures.

The structure is designed more particularly to produce the so-called "grip" for golf clubs, wherein weight and "feel" are vital factors, the former being of particular moment in that the grip producing material or body must not exceed a given weight, or, in other words, must be within such limits as not to throw the club out of balance. Leather in strip form, wound about the shaft, is most commonly employed but such material is open to several objections, among which may be mentioned relatively high cost, "slicking," by reason of use, and variation of "feel" due to several causes, the primary one of which is the weather. Rubber has also been employed as a grip surface (see Letters Patent No. 1,017,565, granted to me under date of February 3, 1912). The grip surface or wrapping as set forth in said patent was placed about the shaft under

tension, a somewhat tedious and troublesome operation; furthermore, such tensioned rubber would break, sometimes shortly after application, unless the rubber employed was of high grade, and consequently was expensive. Again, when kept down within weight limitations the grip would be of relatively short life inasmuch as the stock did not possess sufficient strength when under proper tensioning and would wear out under strain while in use.

The present structure obviates all these objections and while being materially cheaper than leather is as easy of application and as durable in use, presenting a grip, the surface of which remains the same as to "feel" and texture during its life.

The structure is shown in the accompanying drawings, wherein,—

Fig. 1 is a plan view of the preferred form of wrapping or grip element;

Figs. 2, 3 and 4, cross sections on the lines II—II, III—III and IV—IV, respectively, of Fig. 1;

Fig. 5 a side view or edge elevation;

Figs. 6 and 7 plan views showing the invention as applied to narrower strips;

Fig. 8 a perspective view of a still further modification; and

Fig. 9 a side elevation of a shaft or handle having a grip element, as in Fig. 1, applied thereto.

The grip element, Figs. 1 to 5 inclusive, and 9, may be said to comprise a thin tough fabric backing 1 and an overlay of rubber 2. The fabric will be frictioned, as is well understood by those skilled in the rubber art, and the rubber body imposed thereon, the two elements being placed in suitable molds and subjected to vulcanization.

The rubber body will preferably be provided with a series of longitudinally disposed rounded ribs 3, the ribs being of approximately the same height throughout the major portion of the length of the grip strip. Adjacent one end of the strip, say at a distance of approximately 3 inches from the end, the ribs taper down in height, as at 4, and gradually merge into a relatively thin section 5. The cloth or fabric 1 extends beyond the end of the thin section for a slight distance. In the broader aspect of the invention, however, the tapering of the ribs, the flat section and the fabric extension, are not essential.

When a strip such as just outlined is wrapped about the shaft, designated by 6, or upon the listing or other suitable underlay 7, if the same be employed, it will be seen that the ribs and the grooves or depressions formed between the adjacent ribs stand at a relatively sharp angle to the axis of the shaft. This is a point of manifest advantage in the gripping of the club by the user, particularly with reference to that hand which is at the upper end of the club, the fingers crossing the ribs at substantially right angles and ensuring a hold which would otherwise not inhere.

In the application of the grip strip to the shaft or handle, it is not necessary that the same be placed under tension other than that sufficient to cause it to closely adhere and conform to the surface to which it is applied. In this it is different from the grip shown in my patent above referred to,

wherein the strip was placed under more or less tension and held under tension. With the present form, therefore, the life of the grip is materially lengthened and the body 5 may be lighter and conform to the requirements of weight necessarily employed in building up a golf club. The present construction moreover, lends itself to a rapid application of the grip strip to the club or handle. Under the former construction more or less difficulty was encountered in elongating the grip strip or element when the same was wound about the shaft or handle.

10 While I prefer to make the strip of a width of approximately an inch and a quarter, with three ribs thereon, this for the reason that it produces the angularity above referred to, and can be applied more rapidly, 15 it is conceivable that the strip may be formed with only two ribs, or say seven-eighths of an inch wide, as shown in Fig. 6, or of a single strip approximately seven-sixteenths of an inch in width, having a single rib 20 thereon extending from edge to edge, as in Fig. 7.

In Fig. 8 a still further modification of the invention is shown wherein a fabric backing, as 1, is employed in conjunction 25 with an overlay of rubber, rounded or substantially round in cross section, the rubber strip preferably tapering toward the end as under the other constructions, and gradually merging into the fabric underlay.

30 The securing of the grip surface may be done with or without cement in any approved manner, as by tacking the upper end at the beginning of the winding thereof, and likewise tacking the lower end, after 35 which suitable windings, as 8 and 9, may be employed, as usual, in the application of calf grips or the like.

The fact that the rubber is not placed 40 under tension leaves the rubber more or less pliable, depending upon the nature of the rubber and the amount of cure to which it is subjected, thereby producing a grip surface which will conform and yield to the hand slightly and ensures non-slipage of 45 the club or other implement, to which it may be applied, when in use.

50 While I have shown and described the grip strip as tapering in height toward one end, it is to be understood that such construction is not essential and the strip or the ribs thereon may be of the same thickness throughout. The tapering, however, tends to minimize the weight and to produce a finish at the lower end of the grip when 55 applied to a golf club which merges into the body of the club. So, too, in the broader aspect of the invention the ribbed construction is not essential.

While the grip is primarily designed for

use upon golf clubs, it is to be understood 65 that the term "supporting member" as employed in the claims, includes a golf shaft, tool handle, steering wheel, etc.; in fact any element to which the grip would be applicable.

70 What is claimed is,—

1. In combination with a golf shaft; a grip surface therefor wound spirally about the shaft, said surface being produced by a strip imposed thereon, said strip being 75 formed of rubber vulcanized to a fabric underlay, the exposed face of the rubber having a plurality of ribs extending longitudinally of the strip whereby when the strip is positioned they stand at a relatively sharp 80 angle to the axis of the shaft.

2. As a new article of manufacture, a grip surface comprising a strip of fabric having a layer of rubber imposed and vulcanized thereon, the exposed surface whereof is ribbed, the outermost edges of the outermost ribs being substantially coincident with the edges of the fabric strip.

3. As a new article of manufacture a grip surface comprising a strip of fabric having 90 a layer of rubber vulcanized to one face thereof, the exposed face of the rubber having at least one rib extending longitudinally of the strip, the rib decreasing in height toward one end of the strip.

4. As a new article of manufacture a grip surface comprising a strip of fabric having a layer of rubber vulcanized to one face thereof, the exposed face of the rubber having at least one rib extending longitudinally 100 of the strip, the rib decreasing in height toward one end of the strip and merging into a flat relatively thin section.

5. As a new article of manufacture, a grip strip adapted to be wound spirally about a handle or shaft, said strip having a longitudinally ribbed surface, the ribs tapering in height toward one end of the strip.

6. As a new article of manufacture, a grip strip having a plurality of rounded ribs extending longitudinally thereof, said ribs tapering in height toward one end of the strip and the outermost edges of the outermost ribs being substantially coincident with the edges of the strip.

7. As a new article of manufacture, a grip surface comprising a strip of fabric having a layer of rubber vulcanized to one face thereof, the exposed face of the rubber having at least one rounded projection extending longitudinally of the strip, the projection decreasing in height toward one end of the strip and merging into a flat relatively thin rubber section which terminates short of the end of the strip of fabric.

125 In testimony whereof I have signed my name to this specification.

ALLAN E. LARD.
